UNITED STATES PATENT OFFICE.

BENJMIN F. HIGGINS, OF CHRISTOPHER, ILLINOIS.

LOCK

1,109,068.

Specification of Letters Patent.

Patented Sept. 1, 1914.

Application filed February 26, 1914. Serial No. 821,291.

To all whom it may concern:

Be it known that I, BENJMIN F. HIGGINS, a citizen of the United States, residing at Christopher, in the county of Franklin and State of Illinois, have invented certain new and useful Improvements in Locks, of which the following is a specification, reference being had to the accompanying drawings.

10 This invention relates to new and useful improvements in locks and more particularly to a door lock, the main object of the invention being the provision of a lock wherein the locking bolt is connected to the knob
15 spindle, in such a manner that the bolt cannot be turned from the outside, without the use of a key.

Another object of the present invention is the provision of a lock of this character which will possess advantages in points of efficiency and durability, is inexpensive to manufacture and, at the same time, is simple in construction and operation.

With the above and other objects in view, the invention consists in the novel features of construction, combination and arrangement of parts as will be hereinafter referred to and more particularly pointed out in the specification and claim.

30 In the accompanying drawing forming a part of this application, Figure 1 is a horizontal sectional view of a lock constructed in accordance with my invention. Fig. 2 is a transverse sectional view taken on the line 35 2—2, Fig. 1; Fig. 3 is a transverse sectional view taken on the line 3—3, Fig. 2; and Fig. 4 is a front elevation of the door plate.

In carrying out my invention, I provide the door, to which the lock is to be applied, provided with the transverse opening and a longitudinal opening communicating with the transverse opening. This longitudinal opening has a casing indicated by the numeral 1 which is preferably circular in form and mounted therein, is the sliding bolt 2, said bolt being retained in its projected position by means of the coil spring 3, said coil spring encircling the bolt and having one end secured thereto and the other end secured to the casing. Secured to the front edge of the door, is a plate 4, which is provided with a central opening through which the bolt 2 projects, the plate forming a guide for

55 Extending transversely through the door, is a knob spindle 5 provided upon each end

thereof with the knobs indicated by the numerals 6 and 7, the knob 6 being fixed to the spindle in a manner which will be hereinafter and more fully set forth, while the knob 7 rotates independently thereof. A knob 6 is fixed to the spindle 5 through the medium of the wedge member 8 which is slidably mounted within the groove 9 formed in the spindle, the outer end of said wedge member being disposed at right angles, as indicated at 10 and extends out through an opening formed in the sleeve 11, which is carried by the knob 6, whereby turning movement of the knob will rotate the spindle. The outer end of the spindle is provided with a substantially triangularly shaped groove 12 which is adapted to correspond with a similarly shaped groove formed in the inner wall of the opening 13 in the knob 7 so that when the two grooves are brought into registration, they form a substantially rectangular opening adapted to receive the inner end of the key member 14. Thus, when the key is inserted in position, the turning of the knob 7 will rotate the spindle 5. The spindle 5 is provided upon one side thereof with a plurality of openings 15, in which is adapted to be arranged the actuating pin 16, said pin engaging within the slotted end 17 of the bolt 2, so that upon the rotation of the spindle, the bolt 2 will be retracted, in order to open the door.

It will be noted that by having the knob 90
7 loosely mounted upon the outer end of the
spindle 5, the same may be rotated, without
imparting rotary movement to the spindle
and, in order to retract the bolt 2, the key
14 must be first inserted within the register-
ing openings 12 and 13 to connect the spindle
and knob, so that rotary movement may be
readily imparted to the spindle. It will also
be apparent that by connecting the spindle
5 with the knob 6, through the medium of
the wedge member 8, the bolt 2 may be
readily retracted from the inner side of the
door at all times. 95 100

From the foregoing description, it will be readily apparent that I have provided a simple and durable door lock wherein the necessity of providing a separate connection with the locking bolt is eliminated, and the locking bolt is directly connected with the knob spindle so that the door may be readily unlocked by the rotation of the knob, it being necessary to insert a key within the

knob when unlocking the door from the outside. It will also be apparent that my device is extremely simple in construction and can be manufactured at a comparatively low cost.

While I have shown and described the preferred form of my invention, it will be obvious that various changes in the details of construction and in the proportions may 10 be resorted to for successfully carrying my invention into practice, without sacrificing any of the novel features or departing from the scope of the appended claim.

Having thus described this invention, what 15 I claim is:—

A device of the class described including a casing, a locking bolt movable therein having its inner end reduced and provided with an elongated slot, a coil spring mounted 20 upon said reduced end and having one end secured to the casing and the other end bearing against the shoulder formed by the reduced end, whereby the locking bolt is normally retained in its projected position, a

knob spindle, a knob mounted upon one end 25 for rotation with the spindle, a second knob loosely mounted upon the other end and provided with a central opening extending entirely through the knob, said spindle having a triangular recess and 30 said knob having a triangular recess adapted to be arranged in opposed relation with the recess on the spindle to form a rectangular bore, a key member adapted to be inserted within said bore, whereby to rotate 35 the spindle with the rotation of the knob, and a pin carried by the spindle and adapted to be disposed within the slot in the locking bolt, whereby upon the rotation of the knob spindle, the locking bolt will be retracted 40 against the tension of the coil spring.

In testimony whereof I hereunto affix my signature in the presence of two witnesses.

BENJMIN F. HIGGINS.
